Primary Examiner — Bridget L Eland(74) *Attorney, Agent, or Firm* — DLA Piper LLP (US)(57) **CLAIM**

The ornamental design for portable terminal, as shown and described.

DESCRIPTION

FIG. 1 is a front perspective view of a portable terminal showing my new design in a closed state;

FIG. 2 is a front perspective view thereof in an opened state;

FIG. 3 is a front view thereof in the closed state;

FIG. 4 is a rear view thereof in the closed state;

FIG. 5 is a top plan view thereof in the closed state;

FIG. 6 is a bottom view thereof in the closed state;

FIG. 7 is a right side view thereof in the closed state;

FIG. 8 is a left side view thereof in the closed state;

FIG. 9 is a front view thereof in the opened state; and,

FIG. 10 is a rear view thereof in the opened state.

The broken lines immediately adjacent the shaded areas represent the bounds of the claimed design while all other broken lines are directed to environment and are for illustrative purposes only; the broken lines form no part of the claimed design.
